UNITED STATES PATENT OFFICE.

CARL SCHNEIDER, OF NEW YORK, N. Y.

SEWING-MACHINE ATTACHMENT FOR BLINDSTITCHING AND OVERSEAMING.

SPECIFICATION forming part of Letters Patent No. 666,876, dated January 29, 1901.

Application filed December 13, 1898. Serial No. 699,133. (No model.)

To all whom it may concern:

Be it known that I, CARL SCHNEIDER, a citizen of the United States, and a resident of the city of New York, borough of Brooklyn, in the county of Kings and State of New York, have invented a certain new and useful Sewing-Machine Attachment for Blindstitching and Overseaming, of which the following is a specification.

10 The object of this invention is to provide a new and improved sewing-machine attachment for overseaming and blindstitching, which attachment can be used on any sewing-machine and can be applied very easily and rapidly.

In the accompanying drawings, Figure 1 is a plan view of my improved overseaming and blindstitching attachment for sewing-machines. Fig. 2 is a side elevation of the same. 20 Fig. 3 is a vertical transverse sectional view of the same on the line 3 3 of Fig. 1. Fig. 4 is a similar view showing the parts in different positions.

Similar letters of reference indicate like parts in all the figures.

The presser-foot A projects laterally from a plate B, mounted to slide transversely to the length of the presser-foot on the under side of a forked block C, provided with a 30 socket D for receiving the lower end of the presser-bar E, which is held in the socket by a binding-screw E'. A headed screw F is mounted in a cross-piece on the forked piece C in such a manner that said screw can turn axially, but cannot move lengthwise. The screw F is screwed through a block G, located between the shanks or prongs of the forked piece C and extending up between said prongs from the sliding plate B. A screw 35 G' extends upward from said block G, and on the same a nut H is screwed, which rests upon a washer H' on the upper edges of the prongs of the forked block C. By turning the screw F the plate B can be shifted on the 40 under side of the block C in relation to the needle a, and after having been shifted can be locked in place by means of the nut H. Gage-marks a' on the sides of the block C and plate B facilitate such adjustment. The 45 plate B has apertured wings I, through which two pins J extend upward from a base-plate K, which in use is to rest upon the sewing-

plate of the sewing-machine, and may, if desired, be secured after adjustment by means of a screw passed through a slot K' in the 55 plate K and screwed into the sewing-plate. It follows that when the plate B is adjusted by means of the screw F the plate K is adjusted or shifted with it. A recess L is formed in the side edge of the plate K facing 60 the presser-foot A and in the same a pusher M is mounted to slide horizontally and is provided in its outer end with a vertical slit M', through which the needle a can pass, as shown in dotted lines in Fig. 3. The pusher 65 M has an outwardly-extending lug, through which one end of a cam-lever N passes, which is pivotally mounted on the top of plate K and is acted upon by a spring O, (shown in dotted lines,) which presses the inner edge of said lever against a triangular cam-piece P, pivoted on the top of the plate K and made integral with a ratchet-wheel Q, having twice as many teeth as there are cam 70 projections on the cam-piece P. A slide R, 75 mounted to reciprocate on the top of the plate K, has a spring-pawl R, which can engage the teeth of the ratchet-wheel Q and rotate the latter step by step. The slide R is engaged by the lower end of an angle-lever S, 80 pivoted at S' on a standard T on the plate K and acted upon by a spring U. The opposite end of the angle-lever S has a lateral projection V, against which the needle-screw W' on the reciprocating needle-bar W can strike on 85 its upstroke. The presser-foot A has a recess b in its side edge facing the pusher M.

The fabric g is folded, for example, as shown in Figs. 3 and 4, and placed under the presser-foot A, which has been previously adjusted, so 90 as to bring the edge of the base-plate K the proper distance from the needle. As the needle-bar W reciprocates up and down, the screw-head on the same strikes against the projection V on the lever S and swings it upward, whereby the slide R is moved in the direction of arrow X, Fig. 1, and the ratchet-wheel R is turned the distance of one tooth by the pawl P. During the downstroke of the needle-bar the spring U throws the lever 95 S back into the initial position, and so on. The ratchet-wheel Q is thus turned one tooth for every upstroke of the needle-bar, and for every two strokes the cam-piece P is turned 100.

one-third, or, in other words, for each alternate upstroke of the needle-bar the cam-piece is brought in position to press the lever N, and consequently the pusher M, outward, 5 and at the intervening upstrokes the lever N and with it the pusher M are forced back by the spring O. Thus for one downstroke the pusher M is forced out and pushes the fabric g out of the way of the needle a, which passes 10 through the slit M' in the pusher. (See Fig. 3.) At the next downstroke of the needle pusher M is withdrawn, as shown in Fig. 4, and the needle passes through the fabric, and so on. The fabric returns after it has been pushed 15 aside under the action of the tension imparted to it by the presser-foot and cloth-feeder. The blindstitch is produced in the well-known manner by doubling over a fabric so as to present a round doubled-over edge, through 20 which the needle passes at each alternate stroke.

The advantage of a pusher working in a straight line over one operating with a swinging motion will be obvious to any one mechanically inclined. A more solid construction is secured, and perfectly certain operation results, as practical use has demonstrated. Moreover, the pressure is exerted directly against the edge of the fabric, and the 25 elasticity tending to bring it back under the needle is much better preserved than when the fabric is swept to one side by a swinging motion of the pusher.

Having described my invention, what I 30 claim as new, and desire to secure by Letters Patent, is—

1. In an overseaming and blindstitching attachment for sewing-machines, the combi-

nation with a presser-foot having a recess in its inner edge, of a base-plate held on the 40 presser-foot and having a vertical slot in the edge facing the presser-foot and extending inwardly at right angles to said edge; a pusher having a vertical slit and reciprocating in said slot, a cam-lever reciprocating the pusher, 45 said cam-lever being operated by a reciprocating slide mounted on the top of the base-plate and controlled by a spring-lever actuated by the needle-bar, substantially as described. 50

2. In an overseaming and blindstitching attachment for sewing-machines, the combination with a spring-lever contacting with the needle-bar and reciprocating a slide mounted in the top of the base-plate, of a cam-lever 55 controlled by said slide and reciprocating a vertically-slitted pusher in a vertical slot opposite a recessed presser-foot, substantially as described.

3. In an overseaming and blindstitching 60 attachment for sewing-machines, the combination of a slide reciprocated in the base-plate, a spring-pawl attached to said slide and operating a cam-lever, a slitted pusher reciprocating in a vertical slot in the base-plate 65 by said cam-lever, and a recessed presser-foot attached to the base-plate opposite the vertical slot, substantially as described.

Signed at New York, in the county of New York and State of New York, this 9th day of 70 December, A. D. 1898.

CARL SCHNEIDER.
